UNITED STATES PATENT OFFICE

HENRY S. BEERS, OF WESTPORT, CONNECTICUT, ASSIGNOR TO THE TURBO-MIXER CORPORATION, OF NEW YORK, N. Y., A CORPORATION OF NEW YORK

MIXING AND DISCHARGING APPARATUS

Application filed October 24, 1929. Serial No. 401,997.

My invention relates to mixing apparatus including means for conveniently and efficiently discharging the completed mixture, and especially relatively thick or viscous materials, from the mixing tank.

To this end, the invention structure comprises a tank, mixing apparatus therein including a rotor, a sump or discharge chamber adjacent the tank bottom, and means or arrangements by which the rotor may be lowered into the discharge chamber and operated therein to draw the completed mixture from the tank and discharge it to a desired point.

Heretofore, mixing apparatus of the present type, intended for general uses, has not included any definite or adequate means for discharging from the tank after mixing, relatively thick, semi-liquid or viscous materials, of which mayonnaise dressing is one example, and annoyance delay and expense have been involved in removal of such materials in order to clear the tank for reception of a fresh charge. The materials of the class referred to may be described as relatively non-flowing or viscous materials, as contrasted with relatively liquid or readily-flowing materials which will run out of the tank through any simple bottom discharge opening.

In cases where mixers of special types, or intended for mixing materials of particular character, have been provided with discharging means, such means has been independent of or additional to the mixing apparatus proper, or the rotor or impeller thereof, such discharge means consisting for example of a screw or bladed propeller permanently located in a discharge conduit. My invention dispenses with any such distinct or additional discharge apparatus, and provides for the employment of the rotor of the mixer proper as the motive element of the discharge means.

The characteristics and advantages of the invention are further sufficiently explained in connection with the following detail description of the accompanying drawings, which shows one representative embodiment.

After considering this example, skilled per-

sons will understand that many variations may be made without departing from the principles disclosed and I contemplate the employment of any structures that are properly within the scope of the appended claims.

55

Fig. 1 is a vertical section of apparatus embodying the invention in one form.

Fig. 2 is a similar section of the lower part of the apparatus, in discharging condition.

60

Fig. 3 is a section at 3—3, Fig. 2.

Fig. 4 is a section at 4—4, Fig. 1.

The tank 1 has a bottom 2 usually in dished or part-spherical form. At a suitable location, usually near the tank bottom, is mixing apparatus including a rotor or impeller 3. In preferred embodiments, this impeller is of the turbo type, including blades 4, and in such cases, a stationary deflector 5 is usually provided surrounding the impeller. Preferably, also, as shown, the impeller is of duplex type, including curved, annular top and bottom plates 6 connected by the blades 4, which also connect the plates to a hub 7 fixed on the lower end of a shaft 8. In mixing, the impeller is usually located approximately as shown in Fig. 1, substantially above the tank bottom, and the circulated material enters the impeller through the central openings of the top and bottom plates, in downward and upward directions, and is discharged in generally tangential directions between the plates, by the action of blades 4, the circulation of the material in vertical planes being sufficiently explained by arrows in Fig. 1. The deflector is designed to receive the tangentially discharged material and cause it to move in generally radial or axial planes, and for this purpose includes vertical, curved, approximately tangential blades 9, and also may include intermediate blades or plates 10 curved and arranged at alternately upward and downward angles in relation to the horizontal plane, to cause portions of the material to move respectively

80

upward and downward. Except for modifications or arrangements providing for efficient discharge of material from the tank, the impeller and deflector constitute a duplex turbo mixer of known type, as sufficiently

85

90

95

100

understood by skilled persons from the preceding description.

The impeller for present purposes is arranged for vertical movement. The shaft 8 is connected to a sleeve 12. A shaft 13 within the sleeve is connected to it by splines 14 so that the sleeve and shaft 8 are driven by shaft 13 and may move vertically in relation to it. Shaft 13 runs in a bearing 15 in a plate 16 at the top of the tank, and is driven by any suitable driving mechanism such as an electric motor, or gearing in a case 17. The particular driving apparatus or arrangement is not a part of the invention. For the vertical positioning of the impeller, a rack bar 20 is connected to sleeve 12 by a thrust bearing 21. The rack bar slides in a guide 22 on a frame member 23 and is engaged by a pinion 24 on a shaft 25 supported in bearings 26 and 27. A hand wheel 30 is slidably splined on the outer end of the shaft. The hub of the hand wheel has clutch jaws 33 cooperating with complementary jaws 34 on one end of the bearing 27, and is urged to jaw-engaging position by a spring 35 on the shaft. To vertically position the impeller, the hand wheel is retracted from the position of Fig. 4, thus disengaging the clutch jaws. The wheel is then revolved to raise or lower the impeller to desired position, and the wheel is then allowed to return to the position of Fig. 4, with the clutch jaws in engagement, whereupon the impeller is retained in the desired position.

The deflector may be supported in the tank, in such position that it is located about the impeller, when the latter is in normal mixing position as shown in Fig. 1, by any suitable means, such as vertical struts 40 connected to the top of the tank and to a frame or spider 41, which is connected to the deflector. This spider has at its center a hub formation 42 providing a bearing for shaft 8 adjacent the impeller. The deflector 45 may be additionally supported from or braced against the tank bottom, as by vertical struts or legs 44.

At or adjacent the tank bottom is a stump or discharge chamber to cooperate with the impeller when the latter is in discharging position to withdraw the completed mixture from the tank. Specifically, this discharge chamber in a desired form, as shown, is an involute casing 50 corresponding generally to the form of the casing of an involute exhaust apparatus or turbo pump, including a discharge passage or neck 51 through which the material is discharged to any desired point. The involute casing is arranged horizontally, and its upper and lower sides or plates are connected to aligned upper and lower tubular extensions 53 and 54 respectively. The tubular extension or connecting member 53 may be short, and is connected at 65 an opening of the same diameter in the tank

bottom. The lower tubular extension 54 is longer, and dimensioned to receive a piston 56, which slides within the tubes 53 and 54. The piston may be vertically moved and positioned in various ways. As shown, it is carried by a screw 58 which slides through a hole in a supporting block 59 and is prevented from rotating by a key or spline 60. A hand wheel 61 rests on block 59 and has threaded engagement with the screw to adjust the piston in an obvious way. The piston may have any suitable packing means cooperating with the tubes 53 and 54 to prevent leakage of material. Such packing is sufficiently represented herein by the annular channels 65 in the cylindrical surface of the piston.

The material to be mixed may be supplied to the tank in any suitable way as through a pipe 70 leading to a port 71 in the tank wall.

During mixing, the parts are arranged as shown in Fig. 1; that is, piston 56 is elevated so that its upper surface is at the level of the tank bottom and thus forms a closure preventing escape of material. The impeller is located concentrically with the deflector and is rotated to circulate and mix the materials as sufficiently explained above. When mixing is completed, the piston is lowered to the position of Fig. 2, that is, to the lower portion of the lower tubular extension 54 of the involute casing. The impeller is then lowered to the position also shown in Fig. 2, that is, so that the annular discharge opening of the impeller is aligned with the involute casing. The impeller is then rotated at suitable speed and draws the material by powerful suction from the tank, through tube 53 and into the impeller, and discharges the material into 105 and from the casing, the action being that of a rotary turbo-exhauster or pump. The mixed material, even when of semi-fluid, stiff or viscous character is thus quickly and effectively removed from the tank and discharged to any desired point for further handling; the impeller and piston are returned to mixing position, Fig. 1; a new charge is supplied, and the operations are repeated indefinitely.

In its lower position, the piston of course acts as a seal for the lower portion of the involute casing.

The described means for vertically moving the impeller also provides, when desired, for adjustment of the impeller in relation to the deflector, thus affording means for varying or controlling the circulation of material during mixing.

I claim:

1. Mixing and discharging apparatus comprising a tank having a discharge chamber, a rotary material circulator in the tank, and means for positioning the circulator in the

- 5 tank for mixing and in the discharge chamber for discharging material from the tank.
- 6 2. Mixing and discharging apparatus comprising a tank having a bottom discharge chamber, a rotary material circulator in the tank, and means for positioning the circulator in the tank for mixing and in the discharge chamber for discharging material from the tank.
- 7 3. Mixing and discharging apparatus comprising a tank having a discharge chamber, a rotary impeller in the tank, and means for alternatively positioning the impeller in the tank for mixing and in the discharge chamber for discharging mixed material.
- 8 4. Mixing and discharging apparatus comprising a tank having a discharge chamber, a rotary material circulator in the tank, and means for positioning the circulator in the tank for mixing and in the discharge chamber for discharging material from the tank, and a stationary deflector within the tank cooperating with the circulator when in mixing position.
- 9 5. Mixing and discharging apparatus comprising a tank having a discharge chamber, a rotary impeller in the tank, and means for alternatively positioning the impeller in the tank for mixing and in the discharge chamber for discharging mixed material, and a stationary deflector within the tank cooperating with the impeller when in mixing position.
- 10 6. Mixing and discharging apparatus comprising a tank having a discharge chamber, a rotary material circulator in the tank, and means for positioning the circulator in the tank for mixing and in the discharge chamber for discharging material from the tank, and a closure member movable to close the tank bottom during mixing.
- 11 7. Mixing and discharging apparatus comprising a tank having a discharge chamber, a rotary material circulator in the tank, and means for positioning the circulator in the tank for mixing and in the discharge chamber for discharging material from the tank, and a closure member movable to close the tank bottom during mixing, and to form a seal for the discharge chamber during discharging.
- 12 8. Mixing and discharging apparatus comprising a tank having a discharge chamber, a rotary material circulator in the tank, and means for positioning the circulator in the tank for mixing and in the discharge chamber for discharging material from the tank, and a closure member movable to close the tank bottom during mixing, and to form a seal for the discharge chamber during discharging, and in discharging position, admitting the location of the circulator in cooperative relation to the discharge chamber.
- 13 9. Mixing and discharging apparatus comprising a tank having a discharge chamber,
- 14 a rotary impeller in the tank, and means for alternatively positioning the impeller in the tank for mixing and in the discharge chamber for discharging mixed material, and a closure member movable to close the tank bottom during mixing and to form a seal for the discharge chamber during discharging.
- 15 10. Mixing and discharging apparatus comprising a tank, a rotary turbo impeller therein, an involute discharge casing adjacent the tank bottom and arranged to receive the impeller and means for positioning the impeller within the tank for mixing and in the involute casing for discharging material.
- 16 11. Mixing and discharging apparatus comprising a tank, a rotary turbo impeller therein, an involute discharge casing adjacent the tank bottom and arranged to receive the impeller, and means for positioning the impeller within the tank for mixing and in the involute casing for discharging material, and a closure member movable to close the tank bottom during mixing and to close the lower portion of the involute casing during discharging.
- 17 12. Mixing and discharging apparatus comprising a tank, a rotary turbo impeller therein, an involute discharge casing adjacent the tank bottom and arranged to receive the impeller, and means for positioning the impeller within the tank for mixing and in the involute casing for discharging material, the involute casing being connected to the tank bottom by a tubular formation and also having a lower tubular extension of the same diameter, and a piston movable within the tubular formations to close the tank bottom during mixing, and to accommodate the impeller and close the lower portion of the casing during discharging.
- 18 13. Mixing and discharging apparatus comprising a tank, a rotary turbo impeller therein, an involute discharge casing adjacent the tank bottom and arranged to receive the impeller, and means for positioning the impeller within the tank for mixing and in the involute casing for discharging material, and a stationary deflector within the tank about the impeller when the latter is in mixing position.
- 19 14. Mixing and discharging apparatus comprising a tank, a rotary turbo impeller therein, an involute discharge casing adjacent the tank bottom and arranged to receive the impeller, and means for positioning the impeller within the tank for mixing and in the involute casing for discharging material, and a closure member movable to close the tank bottom during mixing and to close the lower portion of the involute casing during discharging, and a stationary deflector within the tank about the impeller when the latter is in mixing position.
- 20 15. Mixing and discharging apparatus comprising a tank having a discharge chamber,

comprising a tank, a discharge chamber, a rotary impeller, the discharge chamber being adapted to receive the impeller, driving means, and a driving connection to the impeller arranged to permit location of the impeller within the tank for mixing and in the discharging chamber for discharging material.

16. Mixing and discharging apparatus comprising a tank, a discharge chamber, a rotary impeller, the discharge chamber being adapted to receive the impeller, driving means, and a driving connection to the impeller arranged to permit location of the impeller within the tank for mixing and in the discharging chamber for discharging material, and means for raising and lowering the impeller and securing it in mixing or discharging position.

20. In testimony whereof I affix my signature.
HENRY S. BEERS.
